19 Claims. (Cl. 260—243)

The present invention concerns 2-substituted-3,4-dihydro-2H-1,2,4-benzothiadiazine-1,1-dioxides. More particularly, it relates to compounds of the formula

in which R₁ represents hydrogen, aliphatic hydrocarbon, substituted aliphatic hydrocarbon, carbocyclic aryl, carbocyclic aryl-lower aliphatic hydrocarbon, heterocyclic aryl or heterocyclic aryl-lower aliphatic hydrocarbon, R_{2'} stands for lower cycloalkyl containing oxygen and/or sulfur atoms as ring members and advantageously have from four to six carbon atoms and at most two atoms selected from the group consisting of sulfur and oxygen as ring members, R_{2''} represents hydrogen or lower alkyl, and R₃ stands for halogen, lower alkyl or halogeno-lower alkyl or salts thereof, as well as process for the preparation of such compounds.

Apart from being hydrogen, R may also stand for aliphatic hydrocarbon radicals, for example, lower aliphatic hydrocarbon, such as lower alkyl, e.g. methyl, ethyl, propyl, isopropyl, butyl, isobutyl, secondary butyl, tertiary butyl, pentyl, isopentyl, neopentyl and the like, lower alkenyl, e.g. vinyl, 1-propenyl, allyl and the like, lower alkynyl, e.g. ethynyl and the like carbocyclic aliphatic hydrocarbons, particularly monocyclic carbocyclic aliphatic hydrocarbons, which contain from three to seven carbon atoms, as ring members and in which the carbocyclic portion may be saturated or may contain from one to two double bonds depending on the number of ring carbon atoms, such as cycloalkyl, which contains from five to six ring carbon atoms, e.g. cyclopentyl, cyclohexyl and the like, or cycloalkenyl, which contains from five to six carbon atoms as ring members, e.g. 2-cyclopentenyl, 3-cyclopentenyl, 2-cyclohexenyl, 3-cyclohexenyl and the like, or carbocyclic aliphatic hydrocarbon-lower aliphatic hydrocarbon, primarily monocyclic carbocyclic aliphatic hydrocarbon-lower alkyl, which contains from three to seven carbon atoms as ring members and in which the carbocyclic portion may be saturated or contain from one to two double bonds depending on the number of ring carbon atoms, and in which lower alkyl represents a lower alkylene radical containing from one to seven, particularly from one to three, carbon atoms, such as cycloalkyl-lower alkyl radicals, which contain from five to six carbon atoms as ring members, e.g. cyclopentylmethyl, 1-cyclopentylethyl, 2-cyclopentylethyl, 1-cyclopentylpropyl, 3-cyclopentylpropyl, cyclohexylmethyl, 1-cyclohexylethyl, 2-cyclohexylethyl, 1-cyclohexylpropyl, 3-cyclohexylpropyl and the like, or cycloalkenyl-lower alkyl radicals, when con-

2

tain from five to six ring carbon atoms, e.g. 2-cyclopentenylmethyl, 3-cyclopentenylmethyl, 2-(2-cyclopentenyl)-ethyl, 2-cyclohexenylmethyl, 3-cyclohexenylmethyl, 1-(3-cyclohexenyl)-ethyl, 2-(2-cyclohexenyl)-ethyl, 3-(2-cyclohexenyl)-propyl and the like.

These aliphatic hydrocarbon radicals may contain functional groups as additional substituents. Such substituents are primarily attached to lower alkyl radicals, which may be represented by a lower alkylene radical containing from one to five carbon atoms, such as, for example, methylene, 1,1-ethylene, 1,2-ethylene, 1,1-dimethyl-1,2-ethylene, 1,1-propylene, 1,2-propylene, 1,3-propylene, 2,3-propylene, 2,2-propylene, 1,1-butylene, 1,2-butylene, 1,3-butylene, 1,4-butylene, 2,2-butylene, 2,3-butylene, 1,5-pentylene, 2,5-pentylene and the like.

Substituents are, for example, one or more than one halogen atom, e.g. fluorine, bromine, or particularly chlorine; halogeno-substituted lower alkyl radicals, representing R₁, are, for example, trifluoromethyl, chloromethyl, 2-chloroethyl, dichloromethyl, trichloromethyl, bromomethyl and the like.

Other substituents are amino groups, such as primary amino groups, secondary amino groups, such as N-lower alkyl-amino, e.g. N-methylamino, N-ethylamino and the like, N-carbocyclic arylamino, e.g. N-phenylamino and the like, or N-carbocyclic aryl-lower alkyl-amino, e.g. N-benzylamino and the like, or primarily tertiary amino groups, particularly N,N-di-lower alkylamino, in which lower alkyl contains from one to seven carbon atoms,

25 e.g. N,N-dimethylamino, N-ethyl-N-methyl-amino, N,N-diethylamino, N,N-di-propylamino, N,N-di-isopropylamino, N,N-dibutylamino and the like, N-cycloalkyl-N-lower alkyl amino, e.g. N-cyclopentyl-N-methyl-amino, N-cyclohexyl-N-methyl-amino and the like, N-carbocyclic aryl-lower alkyl-N-lower alkyl-amino, e.g. N-benzyl-N-methyl-amino, N-methyl-N-(2-phenylethyl)-amino and the like, 1-N,N-lower alkylene-imino group, in which the lower alkylene radical contains from four to six carbon atoms, such as 1-pyrrolidino, e.g. 1-pyrrolidino, 2-methyl-1-pyrrolidino and the like, 1-piperidino, e.g. 1-piperidino, 2-methyl-1-piperidino, 3-methyl-1-piperidino, 4-methyl-1-piperidino, 3-hydroxy-1-piperidino, 3-acetoxy-1-piperidino, 3-hydroxymethyl-1-piperidino and the like, or 1-N,N-hexamethylene-imino, 1-N,N-lower oxa-alkylene-imino, in which oxa-alkylene

30 contains preferably four carbon atoms, e.g. 1-morpholino and the like, or 1-N,N-lower aza-alkylene-imino, in which aza-alkylene contains preferably four carbon atoms, e.g. 1-piperazine, 4-methyl-1-piperazine, 4-hydroxyethyl-1-piperazine, 4-acetoxyethyl-1-piperazine and the like. The tertiary amino group and the lower alkyl radical to which the amino group is attached may present together a heterocyclic radical, in which the tertiary amino group is part of the heterocycle and one of the carbon atoms of the heterocyclic ring is connected directly or through a lower alkylene radical, e.g. methylene or 1,2-ethylene, with the 3-position of the 1,2,4-thiadiazine-1,1-dioxide portion.

Such radicals are, for example, 1-methyl-3-pyrrolidinomethyl, 1-methyl-3-piperidinomethyl, 2-(1-methyl-2-piperidino)-ethyl, 1-methyl-4-piperidino and the like.

Other substituents attached to aliphatic hydrocarbon, particularly lower alkyl, radicals are also N-acylamino groups, in which acyl represents the acyl radical of an organic carboxylic acid, for example, a substituted car-

bionic acid, e.g. methoxy-carbonic acid, ethoxy-carbonic acid, benzyloxy-carbonic acid and the like, a lower aliphatic carboxylic acid, such as a lower alkanoic acid, e.g. acetic, propionic, pivalic acid and the like, lower alkenoic acids, e.g. acrylic, methylacrylic acid and the like, lower aliphatic dicarboxylic acids, e.g. oxalic, malonic, succinic, glutaric, adipic, maleic, fumaric acid and the like, or their halfesters with lower alkanols, e.g. methanol, ethanol and the like, carbocyclic aryl-carboxylic acids, particularly monocyclic carbocyclic aryl-carboxylic acids, e.g. benzoic or substituted benzoic acids, carbocyclic aryl-lower aliphatic carboxylic acids, particularly monocyclic carbocyclic aryl-lower alkyl carboxylic acids, e.g. phenylacetic, diphenylacetic, dihydrocinnamic acid and the like, which may contain additional substituents in the aromatic portion, or monocyclic carbocyclic aryl-lower alkenyl carboxylic acids, e.g. cinnamic acid or substituted cinnamic acids; substituents attached to these carboxylic acids are, for example, lower alkyl, e.g., methyl, ethyl and the like, lower alkoxy, e.g. methoxy, ethoxy and the like, lower alkylenedioxy, e.g. methylenedioxy, nitro, amino, particularly tertiary amino, such as N,N-di-lower alkyl-amino, e.g. N,N-dimethylamino, N,N-diethylamino and the like, halogen, e.g. fluorine, chlorine, bromine and the like, or halogeno-lower alkyl, e.g. trifluoromethyl.

Acyl groups are additional substituents of aliphatic hydrocarbon, particularly lower alkyl radicals, primarily acyl radicals of organic carboxylic acids, such as lower alkanoic acid, e.g. acetic, propionic, butyric acid and the like, as well as substituted carbonic acids, e.g. methoxy-carbonic acid, ethoxy-carbonic acid, benzyloxy-carbonic acid and the like, lower alkenoic acids, e.g. acrylic, methacrylic acid and the like, lower aliphatic dicarboxylic acids, e.g. oxalic, malonic, succinic, glutaric, adipic, maleic, fumaric acid and the like, or their halfesters with lower alkanols, e.g. methanol, ethanol and the like, carbocyclic aryl-carboxylic acids, primarily monocyclic carbocyclic aryl-carboxylic acids, e.g. benzoic or substituted benzoic acids, carbocyclic aryl-lower aliphatic carboxylic acids, primarily monocyclic carbocyclic aryl-lower alkyl carboxylic acids, e.g. phenylacetic, dihydrocinnamic acid and the like, which may contain additional substituents in the aromatic portion, or monocyclic carbocyclic aryl-lower alkenyl carboxylic acids, e.g. cinnamic acid and the like, or substituted cinnamic acids. Additional substituents of these carboxylic acids are, for example, lower alkyl, e.g. methyl, ethyl and the like, lower alkoxy, e.g. methoxy, ethoxy and the like, lower alkylenedioxy, e.g. methylenedioxy, nitro, amino, particularly tertiary amino, such as di-lower alkylamino, e.g. N,N-dimethylamino, N,N-diethylamino and the like, halogen, e.g. fluorine, chlorine, bromine and the like, or halogeno-lower alkyl, e.g. trifluoromethyl.

Other substituents attached to aliphatic hydrocarbon, particularly lower alkyl radicals, are hydroxyl groups. Esterified hydroxyl groups may also be suitable as substituents, especially hydroxyl groups esterified by organic carboxylic acids, for example, substituted carbonic acids, e.g. methoxy-carbonic, ethoxy-carbonic, benzyloxy-carbonic and the like, lower aliphatic carboxylic acids, such as lower alkanoic acids, e.g. acetic, propionic, pivalic acid and the like, lower alkenoic acids, e.g. acrylic, methylacrylic acid and the like, lower aliphatic dicarboxylic acids, e.g. oxalic, malonic, succinic, glutaric, adipic, maleic, fumaric acid and the like, or their halfesters with lower alkanols, e.g. methanol, ethanol and the like, carbocyclic aryl-carboxylic acids, primarily monocyclic carbocyclic aryl-carboxylic acids, e.g. benzoic or substituted benzoic acids, carbocyclic aryl-lower aliphatic carboxylic acids, primarily monocyclic carbocyclic aryl-lower alkyl carboxylic acids, e.g. phenylacetic, dihydrocinnamic acid and the like, which may contain additional substituents in the aromatic portion, or monocyclic carbocyclic aryl-lower alkenyl carboxylic acids, e.g. cinnamic acid and the like,

5 the like, or substituted cinnamic acids. Substituents of such carboxylic acids, are, for example, lower alkyl, e.g. methyl, ethyl and the like, lower alkoxy, e.g. methoxy, ethoxy and the like, lower alkylenedioxy, e.g. methylenedioxy, nitro, amino, particularly tertiary amino, such as di-lower alkyl-amino, e.g. N,N-dimethylamino, N,N-diethylamino and the like, halogen, e.g. fluorine, chlorine, bromine and the like, or halogeno-lower alkyl, e.g. trifluoromethyl.

10 Further substituents of aliphatic hydrocarbon radicals, particularly lower alkyl radicals, are etherified hydroxyl groups, which may be represented, for example, by aliphatic hydrocarbonoxy, such as lower alkoxy, e.g. methoxy, ethoxy, n-propoxy, isopropoxy, n-butoxy, isobutoxy and the like, lower alkenyloxy, e.g. vinyloxy, allyloxy and the like, carbocyclic aryloxy, such as monocyclic carbocyclic aryloxy, e.g. phenoxy or substituted phenoxy, or bicyclic carbocyclic aryloxy, e.g. 1-naphthoxy or 2-naphthoxy or substituted naphthoxy, or carbocyclic aryl-aliphatic hydrocarbonoxy, such as monocyclic carbocyclic aryl-lower alkoxy, e.g. benzyloxy or substituted benzyloxy. The aliphatic hydrocarbon, and particularly the carbocyclic aryl portions of the etherified hydroxyl groups may contain additional substituents; such substituents are, for example, lower alkyl, e.g. 15 methyl, ethyl and the like, lower alkoxy, e.g. methoxy, ethoxy and the like, lower alkylenedioxy, e.g. methylenedioxy, nitro, amino, particularly tertiary amino, such as N,N-di-lower alkyl-amino, e.g. N,N-dimethylamino, N,N-diethylamino and the like, halogen, e.g. fluorine, chlorine, bromine and the like, or halogeno-lower alkyl, e.g. 20 trifluoromethyl.

25 In addition, aliphatic hydrocarbon, particularly lower alkyl, radicals may be substituted by an etherified mercapto group, for example, aliphatic hydrocarbon-mercapto, such as lower alkyl-mercapto, e.g. methyl-mercapto, ethyl-mercapto, n-propyl-mercapto, isopropyl-mercapto, n-buty1-mercapto, isobutyl-mercapto and the like, lower alkenyl-mercapto, e.g. vinyl-mercapto, allyl-mercapto and the like, carbocyclic aryl-mercapto, such as monocyclic carbocyclic aryl-mercapto, e.g. phenyl-mercapto or substituted phenyl-mercapto, or bicyclic carbocyclic aryl-mercapto, e.g. 1-naphthyl-mercapto or 2-naphthyl-mercapto or substituted naphthyl-mercapto, or carbocyclic aryl-aliphatic hydrocarbon-mercapto, primarily monocyclic carbocyclic aryl-lower alkyl-mercapto, e.g. benzyl-mercapto, 1-phenylethyl-mercapto, 2-phenylethyl-mercapto and the like, or substituted benzyl-mercapto, substituted 1-phenylethyl-mercapto, substituted 2-phenylethyl-mercapto and the like. The aliphatic hydrocarbon portions and, particularly, the carbocyclic aryl portions of the etherified mercapto groups may contain additional substituents; such substituents are, for example, lower alkyl, e.g. methyl, ethyl and the like, lower alkoxy, e.g. 30 methoxy, ethoxy and the like, lower alkylenedioxy, e.g. methylenedioxy, nitro, amino, such as primary or secondary amines, or, particularly, tertiary amino, such as N,N-di-lower alkyl-amino, e.g. N,N-dimethylamino, N,N-diethylamino and the like, halogen, e.g. fluorine, chlorine, bromine and the like, halogeno-lower alkyl, e.g. trifluoromethyl.

35 Apart from aliphatic hydrocarbon radicals R_1 may represent carbocyclic aryl groups, such as monocyclic carbocyclic aryl, e.g. phenyl or substituted phenyl, or monocyclic carbocyclic aryl, e.g. 1-naphthyl or 2-naphthyl or substituted naphthyl radicals, or carbocyclic aryl-aliphatic hydrocarbon radicals, particularly monocyclic or bicyclic carbocyclic aryl-lower alkyl, e.g. benzyl, 1-phenylethyl, 2-phenylethyl, 3-phenylpropyl, 1-naphthylmethyl and the like, or these radicals substituted in the carbocyclic aryl portion, or monocyclic or bicyclic carbocyclic aryl-lower alkenyl, e.g. 2-phenyl-ethenyl and the like, as well as such radicals containing in the carbocyclic portion additional substituents. Such substituents are, 40 for example, lower alkyl, e.g. methyl, ethyl and the like,

lower alkoxy, e.g. methoxy, ethoxy and the like, lower alkylenedioxy, e.g. methylenedioxy, lower alkyl mercapto, e.g. methylmercapto and the like, amino, particularly tertiary amino, such as N,N-di-lower alkyl-amino, e.g. dimethylamino and the like, halogen, e.g. fluorine, chlorine, bromine and the like, or halogeno-lower alkyl, e.g. trifluoromethyl. Substituents attached to carbocyclic aryl, particularly monocyclic carbocyclic aryl portions may be in any of the available positions, whereby one or more than one of the same or of different substituents may be present.

Additional groups representing R₁ are heterocyclic aryl radicals, particularly monocyclic or bicyclic heterocyclic aryl radicals, which may contain from five to six atoms as ring members in the heterocyclic portion, such as pyridyl, e.g. 2-pyridyl, 3-pyridyl, 4-pyridyl and the like, thienyl, e.g. 2-thienyl and the like, furyl, e.g. 2-furyl and the like, or quinolyl, e.g. 6-quinolyl and the like, or heterocyclic aryl-aliphatic hydrocarbon, such as monocyclic heterocyclic-aryl-lower alkyl, for example, phenyl, e.g. 2-phenyl and the like. These radicals may contain additional substituents, particularly lower alkyl, e.g. methyl, ethyl and the like, lower alkoxy, e.g. methoxy, ethoxy and the like, or halogen, e.g. fluorine, chlorine, bromine and the like.

The radical R₂' stands for lower cycloalkyl containing oxygen and/or sulfur atoms as ring members. These groups have advantageously from four to six carbon atoms and at most two atoms selected from the group consisting of sulfur and oxygen as ring members.

The carbon atoms of the lower cycloalkyl nucleus may be unsubstituted or substituted by lower hydrocarbon, particularly lower alkyl, e.g. ethyl, n-propyl, isopropyl, or especially methyl and the like; other substituents may be, for example, lower cycloalkyl, e.g. cyclopentyl or cyclohexyl and the like, monocyclic or bicyclic carbocyclic aryl, e.g. phenyl or naphthyl, monocyclic or bicyclic carbocyclic aryl-lower alkyl, e.g. benzyl, 1-phenylethyl or 2-phenylethyl and the like. Two of the carbon atoms of the lower cycloalkyl nucleus may also be part of a second carbocyclic ring system fused onto the lower cycloalkyl nucleus; such carbocyclic ring systems may be represented, for example, by lower cycloalkyl containing from five to seven carbon atoms, e.g. cyclopentyl, cyclohexyl or cycloheptyl and the like, or carbocyclic aryl, such as monocyclic or bicyclic carbocyclic aryl, e.g. phenyl or naphthyl.

The cycloalkyl radical, R₂', may, therefore, be represented primarily by cyclo-oxa-alkyl containing from four to six carbon atoms, such as tetrahydrofuranyl (cyclo-oxapentyl) radicals, such as 2-tetrahydrofuranyl (2-cyclo-oxapentyl) radicals, e.g. 2-tetrahydrofuranyl (2-cyclo-oxapentyl), 4-methyl-2-tetrahydrofuranyl (4-methyl-2-cyclo-oxapentyl) or 5-methyl-2-tetrahydrofuranyl (5-methyl-2-cyclo-oxapentyl) and the like, tetrahydropyranyl (cyclo-oxahexyl) radicals, such as 2-tetrahydropyranyl (2-cyclo-oxahexyl) radicals, e.g. 2-tetrahydropyranyl (2-cyclo-oxahexyl), 2-methyl-2-tetrahydropyranyl (2-methyl-2-cyclo-oxahexyl), 4-methyl-2-tetrahydropyranyl (4-methyl-2-cyclo-oxahexyl), 6-methyl-2-tetrahydropyranyl (6-methyl-2-cyclo-oxahexyl), 6-phenyl-2-tetrahydropyranyl (6-phenyl-2-cyclo-oxahexyl), 2-hexahydrobenz[e]tetrahydropyranyl (bicyclo[4,4,0]-2-oxa-3-decyl), or 2-benz[e]tetrahydropyranyl (2-benz[e]cyclo-oxahexyl) and the like, cyclo-oxaheptyl radicals, such as 2-cyclo-oxaheptyl radicals, e.g. 2-cyclo-oxaheptyl, and the like, dioxanyl (cyclo-dioxahehexyl) radicals, such as 2-(1,4-dioxanyl) (2-cyclo-dioxahehexyl) radicals, e.g. 2-(1,4-dioxanyl) (2-cyclo-1,4-dioxahehexyl) and the like, tetrahydro-oxathiinyl (cyclo-oxathiahexyl) radicals, such as 2-tetrahydro-oxathiinyl (2-cyclo-1,4-oxathiahexyl) radicals, e.g. 2-tetrahydro-oxathiinyl (2-cyclo-1,4-oxathiahexyl) and the like, tetrahydrothienyl (cyclo-thiapentyl) radicals, such as 2-tetrahydrothienyl (2-cyclo-thiapentyl) radicals, e.g. 2-tetrahydrothienyl and the like,

in which compounds R_3 stands for chlorine or trifluoromethyl, and lower alkyl contains from one to four carbon atoms, and R_2' is defined as above. Particularly active compounds are, for example,

- 6-chloro-2-(2-cyclo-oxapentyl)-3-methyl-7-sulfamyl-3,4-dihydro-2H-1,2,4-benzothiadiazine-1,1-dioxide,
 6-trifluoromethyl-2-(4-methyl-2-cyclo-oxapentyl)-3-methyl-7-sulfamyl-3,4-dihydro-2H-1,2,4-benzothiadiazine-1,1-dioxide,
 6-chloro-2-(2-cyclo-oxapentyl)-3-methyl-7-sulfamyl-3,4-dihydro-2H-1,2,4-benzothiadiazine-1,1-dioxide,
 6-trifluoromethyl-2-(4-methyl-2-cyclo-oxapentyl)-3-methyl-7-sulfamyl-3,4-dihydro-2H-1,2,4-benzothiadiazine-1,1-dioxide,
 6-chloro-2-(5-methyl-2-cyclo-oxapentyl)-3-isobutyl-2-methyl-7-sulfamyl-3,4-dihydro-2H-1,2,4-benzothiadiazine-1,1-dioxide,
 6-trifluoromethyl-2-(2-cyclo-oxahexyl)-3-isobutyl-2-methyl-7-sulfamyl-3,4-dihydro-2H-1,2,4-benzothiadiazine-1,1-dioxide,
 6-chloro-2-(2-methyl-2-cyclo-oxahexyl)-3-dichloromethyl-2-methyl-7-sulfamyl-3,4-dihydro-2H-1,2,4-benzothiadiazine-1,1-dioxide,
 3-dichloromethyl-6-trifluoromethyl-2-(4-methyl-2-cyclo-oxahexyl)-7-sulfamyl-3,4-dihydro-2H-1,2,4-benzothiadiazine-1,1-dioxide,

each of which is substituted in the 3-position by a lower cyclo-alkyl group containing oxygen and/or sulfur atoms as ring members and advantageously having from four to six carbon atoms and at most two hetero (S or O) ring members.

The new compounds of this invention may be used as medicaments in the form of pharmaceutical preparations, 15 which contain the new 2-substituted-3,4-dihydro-2H-1,2,4-benzothiadiazine-1,1-dioxide compounds or the salts thereof in admixture with a pharmaceutical organic or inorganic, solid or liquid carrier suitable for enteral, e.g. oral, or parenteral administration. For making up the 20 preparations there can be employed substances which do not react with the new compounds, such as water, gelatine, lactose, starches, stearic acid, magnesium stearate, stearyl alcohol, talc, vegetable oils, benzyl alcohols, gums, waxes, propylene glycol, polyalkylene glycols or 25 any other known carrier for medicaments. The pharmaceutical preparations may be in solid form, for example, as capsules, tablets or dragees, or in liquid form, for example, as solutions, suspensions or emulsions. If desired, they may contain auxiliary substances such as 30 preserving agents, stabilizing agents, wetting or emulsifying agents, salts for varying the osmotic pressure or buffers. They may also contain, in combination, other therapeutically useful substances; particularly useful are 35 antihypertensive compounds, such as Rauwolffia alkaloids, e.g. reserpine, rescinnamine or deserpidine, semisynthetic Rauwolffia alkaloids, e.g. syrosingopine and the like, Veratrum alkaloids, e.g. germine, protoveratrine and the like, synthetic antihypertensive compounds, e.g. hydralazine, dihydralazine and the like, or ganglionic blockers, e.g. chlorisondamine and the like.

The compounds of the present invention may be prepared according to methods which are known in themselves.

Thus, compounds of the formula

50 in which R_1 , R_2' , R_2'' and R_3 have the previously-given meaning may be prepared, for example, by treating a 3,4-dihydro-2H-1,2,4-benzothiadiazine-1,1-dioxide of the formula

in which R_1 , R_2'' and R_3 have the previously-given meaning, or an alkali metal salt thereof, with a cycloalkene 65 containing oxygen and/or sulfur atoms as ring members, which is capable of introducing the radical R_2' in the presence of a condensing agent, and isolating the desired product, and, if desired, converting a resulting salt into the free compound, and/or, if desired, converting a free 70 compound into a salt thereof.

The above-mentioned lower cycloalkene reagents are more particularly 2-cycloalkenes containing at most two atoms selected from the group consisting of oxygen and sulfur and from four to six carbon atoms as ring members. Such compounds are, for example, 2-cyclo-oxa-

alkenes containing from four to six carbon atoms as ring members, such as dihydrofurans (2-cyclo-oxapentenes), e.g. dihydrofuran (2-cyclo-oxapentene), 4-methyl-dihydrofuran (4-methyl-2-cyclo-oxapentene), or 5-methyl-dihydrofuran (5-methyl-2-cyclo-oxapentene) and the like, dihydropyrans (2-cyclo-oxahexenes), e.g. dihydropyran (2-cyclo-oxahexene), 2-methyl-dihydropyran (2-methyl-2-cyclo-oxahexene), 4-methyl-dihydropyran (4-methyl-2-cyclo-oxahexene), 6-methyl-dihydropyran (6-methyl-2-cyclo-oxahexene), 6-phenyl-dihydropyran (6-phenyl-2-cyclo-oxahexene), hexahydro-benz[e]dihydropyran (bi-cyclo[4,4,0]-2-oxa-3-decene) or 2-benz[e]dihydropyran (2-benz[e]cyclo-oxahexene) and the like, 2-cyclo-oxaheptenes, e.g. 2-cyclo-oxaheptene and the like, dihydrodioxines (2-cyclo-dioxahexenes), such as dihydro-1,4-dioxines (2-cyclo-1,4-dioxahexenes), e.g. dihydro-1,4-dioxine (2-cyclo-1,4-dioxahexene) and the like, dihydro-oxathiins (2-cyclo-oxathiahexenes), such as dihydro-1,4-oxathiins (2-cyclo-1,4-oxathiahexenes), e.g. dihydro-1,4-dioxathiin (2-cyclo-1,4-oxathiahexene) and the like, dihydrothiophenes (2-cyclo-thiapentene), e.g. dihydrothiophene (2-cyclo-thiapentene) and the like, dihydrothiopyrans (2-cyclo-thiahexenes), e.g. dihydrothiopyran (2-cyclo-thiahexene) and the like, or dihydro-dithiins (2-cyclo-dithiahexenes), such as dihydro-1,4-dithiins (2-cyclo-1,4-dithiahexenes), e.g. dihydro-1,4-dithiin (2-cyclo-1,4-dithiahexene) and the like.

These reagents, particularly the 2-cyclo-oxa-alkenes containing from four to six carbon atoms as ring members, such as dihydropyrans, e.g. dihydropyran, are reacted with the deserpitate compound in the presence of a condensing reagent, particularly an acidic condensing reagent represented by a Lewis acid. Such Lewis acids are, for example, mineral acids, e.g. hydrochloric, hydrobromic or sulfuric acid (used in anhydrous form or as concentrated aqueous solutions), phosphoric acid (for example, in the form of polyphosphoric acid), phosphorous oxychloride, fluoboric acid (in the form of a highly concentrated aqueous solution), borontrifluoride (in the form of its etherate, particularly with diethyl ether), or a carbocyclic aryl sulfonic acid, such as a monocyclic carbocyclic acid, especially p-toluenesulfonic acid, or similar reagents having Lewis acid properties, such as, for example, cation exchange resins in acid form, e.g. sulfonic acid resins.

The reaction may be carried out in the absence of a solvent, whereby an excess of a liquid cycloalkene may serve as the solvent, or in the presence of an inert solvent. Such solvents are, for example, carbocyclic aryl hydrocarbons, such as monocyclic carbocyclic aryl hydrocarbons, e.g. benzene or toluene and the like, ethers, e.g. diethylether or tetrahydrofuran and the like, lower alkanes, e.g. acetone or ethyl methyl ketone and the like, formamides, e.g. formamide or N,N-dimethylformamide and the like.

The desired product is isolated from the reaction mixture according to usual methods; ordinarily, a resulting precipitate, if necessary after concentration of the reaction mixture, is filtered off and is purified by recrystallization.

The 3,4-dihydro-2H-1,4-benzothiadiazine-1,1-dioxides used as the starting materials are known or may be prepared according to procedures used for the known analogs. For example, an aniline compound of the formula

in which $\text{R}_{2''}$ and R_3 have the previously-given meaning is reacted with an aldehyde of the formula $\text{R}_1\text{--CHO}$, in which R_1 has the previously-given meaning, or a reactive derivative thereof, to form the desired 3,4-dihydro-2H-

1,2,4-benzothiadiazine-1,1-dioxide, which may then be condensed with the desired cyclo-oxa-alkene or cyclo-aza-alkene to yield the $\text{R}-\text{R}_2'$ -substituted product, R_2' having the previously-given meaning.

5 Although the disulfamyl-aniline compound is preferably treated with approximately an equivalent amount of the aldehyde, particularly when formaldehyde or a reactive derivative, e.g. a polymer thereof is used, an excess of an aldehyde other than formaldehyde or a derivative thereof may be present. The reaction may advantageously be carried out in the presence of a small amount of an acid, for example, a mineral acid, e.g. hydrochloric, hydrobromic acid, sulfuric acid and the like, if desired, in anhydrous form. An acid is necessary, if the aldehyde is present in the form of a reactive derivative, such as a polymer or an acetal, thereof. It may also be performed in the absence of a condensing reagent, or in the presence of a base, such as an alkali metal hydroxide, e.g. lithium, sodium or potassium hydroxide, whereby the aldehyde is used in its reactive form. As mentioned above, the aldehyde may also be given into the reaction medium in a form which yields the desired reactant in situ. Thus, for example, an acetal of an aldehyde $\text{R}_1\text{--CHO}$ with lower alkanols, for example, with methanol or ethanol, may be used in the presence of a mineral acid; such acetals are, for example, 1,1-dimethoxyethane, 1,1-dimethoxy-isobutane, 1,1-diethoxy-isobutane, 2,2-dichloro-1,1-dimethoxyethane, 2,2-dichloro-1,1-diethoxy-ethane and the like. Formaldehyde may also be employed in the form of a polymer, such as, for example, paraformaldehyde and the like or another formaldehyde furnishing reagent, e.g. hexamethylenetetramine and the like; acetaldehyde may be present in the form of a polymeric substance yielding acetaldehyde under the condition of the reaction, e.g. 35 metaldehyde and the like.

The reaction is preferably carried out in the presence of a solvent, for example, an ether, e.g. p-dioxane, diethyleneglycol dimethylether and the like, a lower alkanol, e.g. methanol, ethanol and the like, a formamide, e.g. dimethylformamide and the like, or an aqueous mixture of such solvents or water. If desired, it may be completed at an elevated temperature, for example, on the steam bath or at the boiling temperature of the solvent and, if necessary, the reaction may be performed under increased pressure or in the atmosphere of an inert gas, e.g. nitrogen.

The $5\text{-R}_3\text{-2,4-disulfamyl-anilines}$, used as the intermediates in the above reaction are known or, if new, may be prepared according to known procedures.

50 The compounds of the present invention may also be prepared by reacting a 2,4-disulfamyl-aniline of the formula

55 in which R_2' , $\text{R}_{2''}$ and R_3 have the previously-given meaning, with an aldehyde of the formula $\text{R}_1\text{--CHO}$, in which R_1 has the above-given meaning, or a reactive derivative thereof, and, if desired, carrying out the optional steps.

The above reaction may be performed according to the previously-described method for the preparation of 2-unsubstituted 3,4-dihydro-2H-1,2,4-benzothiadiazine-1,1-dioxides used as the starting materials in the first modification of the process of this invention. For example, the two reactants may be heated in a solution using one of the previously-described diluents, if desired, in the presence of a base as a condensing reagent. As pointed out, the aldehyde may also be used in the form of an appropriate reactive derivative.

75 The 2 - (N- R_2' -sulfamyl) - 4 - sulfamyl-5- $\text{R}_3\text{-N-}\text{R}_{2''}$ -aniline compounds used as the starting materials, are new

11

and are intended to be included within the scope of the invention. The compounds of the formula

in which R_2' , R_2'' and R_3 have the previously-given meaning, may be obtained by reacting an aniline-2,4-disulfonyl halide of the formula

in which R_2'' and R_3 have the previously-given meaning, and Hal stands for halogen, particularly chlorine, with approximately two molar equivalents of an amine of the formula $R_2'-NH_2$, in which R_2' has the above-given meaning, and reacting the resulting compound of the formula

in which R_2' , R_2'' , R_3 and Hal have the previously-given meaning, with ammonia.

The first step in the above procedure may be carried out in a solvent; halogenated alkanes, particularly chloroform, methylene chloride and the like, or lower alkanones, e.g. acetone and the like, may be used as diluents. Amines of the formula $R_2'-NH_2$ are those in which the term R_2' has the meaning given above.

The resulting 2-(N - R_2' -sulfamyl)-aniline-4-sulfonyl halide compound may be separated from any 2,4-di-(N - R_2' -sulfamyl)-aniline formed in the reaction, for example, on the basis of their different solubilities in a given solvent, e.g. the diluent used in the reaction. Thus, the 2,4-bis-(N - R_2' -sulfamyl)-aniline compound may precipitate from the reaction mixture and be removed by filtration, whereas the desired 2-(N - R_2' -sulfamyl)-aniline-4-sulfonyl halide compound may be recovered from the filtrate.

The resulting 2-(N - R_2' -sulfamyl)-aniline-4-sulfonyl halide derivative is then reacted with ammonia. Liquid ammonia may be used and may simultaneously serve as a diluent, or the compound may be dissolved in an organic solvent, e.g. acetone and the like, or less favorably, in water, and be treated with concentrated aqueous ammonia, to give the desired 2-(N - R_2' -sulfamyl)-4-sulfamyl-aniline compound.

It may also be possible to omit the separation of the desired 2-(N - R_2' -sulfamyl)-aniline-4-sulfonyl halide from any 2,4-bis-(N - R_2' -sulfamyl)-aniline compound simultaneously formed as a by-product; a resulting mixture may be reacted directly with ammonia directly and separation of the two products may be achieved after such treatment.

Especially useful as intermediates are the compounds of the formula

in which R_2' represents 2-cycloalkenes containing at most two atoms selected from the group consisting of oxygen and sulfur and from four to six carbon atoms as ring members, as enumerated above.

12

Also new and valuable as intermediates are the compounds of the formula

in which R_2' , R_2'' , R_3 and Hal have the previously-given meaning, which are formed in the two-step synthesis for the preparation of the starting materials. A preferred group of such new intermediate compounds are those of the formula

in which R_2' and R_3 have the meaning given above. Also included within the scope of the present invention are the compounds of the formula

in which R_1 , R_2' , R_2'' and R_3 have the previously-given meaning, and R_2''' stands for aliphatic hydrocarbon, substituted aliphatic hydrocarbon or carbocyclic aryl-lower aliphatic hydrocarbon, or metal, particularly alkali metal, salts thereof.

The compounds of the above-given formula have diuretic and saluretic, particularly natriuretic properties and are intended to be used as diuretic or saluretic, particularly natriuretic agents having improved and outstanding properties to relieve conditions of excessive water and salt retention, for example, those connected with kidney or heart ailments. Coupled with the diuretic and saluretic activities of these compounds is a strong antihypertensive effect, which renders the compounds especially useful as antihypertensive medicaments in hypertensive conditions, which are coupled with water and salt retention, such as, for example, in heart ailments. Particularly outstanding diuretic and saluretic effects are shown by compounds of the formula

in which R_1 represents hydrogen, lower alkyl, e.g. methyl, ethyl, n-propyl, isopropyl, n-butyl, isobutyl and the like, or lower alkyl substituted by halogen, lower alkoxy, lower alkyl-mercapto, phenyl-lower alkyl-mercapto and the like, e.g. chloromethyl, dichloromethyl, ethoxymethyl, ethyl mercaptoethyl, benzylmercaptoethyl and the like, lower alkenyl, e.g. 1-propenyl and the like, cycloalkyl containing from five to six carbon atoms as ring members, e.g. cyclopentyl and the like, or phenyl-lower alkyl, e.g. benzyl, 2-phenylethyl and the like, the radical R_2' stands for lower cycloalkyl containing oxygen and/or sulfur atoms as ring members and advantageously from four to six carbon atoms and at most two atoms selected from the group consisting of sulfur and oxygen as ring members and R_2''' stands for lower alkyl containing from one to four carbon atoms, e.g. methyl, ethyl, n-propyl, isopropyl, n-butyl, isobutyl and the like, allylic lower alkenyl containing from three to five carbon atoms, e.g. allyl, 2-methylallyl, 3-methyl-allyl and the like, or phenyl-lower alkyl, in which lower alkyl contains from one to four carbon atoms, e.g. benzyl, 1-phenylethyl, 2-phenylethyl and the

like, and R_3 stands for halogen, e.g. fluorine, bromine, or particularly chlorine, or halogeno-lower alkyl, e.g. trifluoromethyl, and sodium or potassium salts thereof. This group of compounds may be represented by the compounds of the formula

in which formulae R_3 represents chlorine or trifluoromethyl, lower alkyl contains from one to four and lower alkenyl from three to five carbon atoms, as well as compounds of the above formulae, which contain in the 3-position a lower alkyl radical containing from one to four carbon atoms, particularly methyl, ethyl, isobutyl and the like, halogeno-lower alkyl, in which lower alkyl contains from one to four carbon atoms, e.g. chloromethyl, dichloromethyl and the like, or phenyl-lower alkyl, in which lower alkyl contains from one to four carbon atoms, e.g. benzyl, 1-phenylethyl, 2-phenylethyl and the like.

Similarly, as with the previously-described compounds containing an N-unsubstituted sulfamyl group in the 7-position, the compounds of the above formula may be formulated into pharmaceutical compositions for enteral, e.g. oral, or parenteral application; such compositions may be prepared according to known procedures, using standard vehicles and fillers.

The above-described compounds may be prepared, for example, by treating a compound of the formula

in which R_1 , R_2' , R_2'' and R_3 have the previously-given meaning, with a reactive ester of an alcohol of the formula $R_2'''-OH$, in which R_2''' has the above-given meaning, or treating a compound of the formula

in which R_2' , R_2'' , R_2''' and R_3 have the previously-given meaning, with an aldehyde of the formula R_1-CHO , in which R_1 has the above-given meaning, or a reactive derivative thereof and, if desired, converting a resulting salt into the free compound, and/or, if desired, converting a free compound into a salt thereof.

The above reactions are carried out according to the previously-described procedures. For example, an ester of a reactive alcohol of the formula $R_2'''-OH$ is particularly an ester with a strong acid, particularly a mineral acid, e.g. hydrochloric, hydrobromic, sulfuric acid and the like, or an organic sulfonic acid, e.g. methane sulfonic, ethane sulfonic, 2-hydroxy-ethane sulfonic, p-tolu-

ene sulfonic acid and the like; such esters are preferably reacted with a salt, particularly an alkali metal salt of the starting material. Or, an aldehyde of the formula R_1-CHO may also be used in the form of an acetal with a lower alkanol, e.g. methanol, ethanol and the like. Formaldehyde or acetaldehyde may be present as a polymeric form thereof, e.g. paraformaldehyde, metaldehyde and the like; other reactive forms furnishing formaldehyde are, for example, hexamethylenetetramine and the like. Reactions with such acetals and polymeric forms of aldehydes are carried out in the presence of an acid, for example, a mineral acid, e.g. hydrochloric acid and the like.

Compounds of the formula

15

20

in which R_1 , R_2' , R_2'' , R_2''' and R_3 have the previously-given meaning, and R_2' and R_2''' stand for the identical group, may also be prepared by reacting a compound of the formula

25

30

in which R_1 , R_2'' and R_3 have the above-given meaning with an excess of a reactive ester of an alcohol of the formula $R_2'-OH$, in which R_2' has the previously-given meaning, and isolating the desired compound, and, if desired, carrying out the optional steps.

The reaction may be performed as previously shown; the desired product is separated from any simultaneously formed 3,4-dihydro-2H-1,2,4-benzothiadiazine-1,1-dioxide containing an unsubstituted sulfamyl group in the 7-position, on the basis of differing solubilities in solvents, for example, by recrystallization and the like.

The resulting product may be obtained in the form of the free compound or as a salt thereof. An alkali metal salt may be converted into the free compound by treatment with an aqueous acidic reagent, such as a mineral acid, e.g. hydrochloric, sulfuric acid and the like. A free compound may be converted into an alkali metal salt, for example, by treatment with an alkali metal hydroxide, e.g. sodium or potassium hydroxide, in a solvent, such as in a lower alkanol, e.g. methanol, ethanol and the like, or in water and evaporating the solvent. Mono- or poly-salts may be obtained.

Any resulting racemate may be converted into the antipodes thereof according to methods used for resolving racemates.

The following examples illustrate the invention; they are not to be construed as being limitations thereon. Temperatures are given in degrees centigrade.

60

Example 1

To 2.55 g. of 6-chloro-3,4-dihydro-7-sulfamyl-1,2,4-benzothiadiazine-1,1-dioxide in 35-40 cc. of warm acetone is added 0.84 g. dihydropyran and two drops concentrated hydrochloric acid. The solution is allowed to remain at room temperature overnight, then concentrated to dryness in vacuo. A small amount of ether is added to the residue and white crystals are obtained, yielding, when recrystallized from acetone, 600 mg. 6-chloro-3,4-dihydro-7-sulfamyl-2-(tetrahydro-2-pyranyl)-1,2,4-benzothiadiazine-1,1-dioxide; M.P. 231-232°d.

[By substituting an equivalent amount of 6-trifluoromethyl-3,4-dihydro-7-sulfamyl-1,2,4-benzothiadiazine-1,1-dioxide for the 6-chloro-3,4-dihydro-7-sulfamyl-1,2,4-benzothiadiazine-1,1-dioxide and following the procedure

given above, the corresponding 6-trifluoromethyl compound may be obtained. Using the identical procedure and any of the other cyclo-oxa-alkyl or cyclo-aza-alkyl reactants named above, corresponding products may be obtained, as is evident below.]

Example 2

2.55 g. of 6-chloro-3,4-dihydro-7-sulfamyl-1,2,4-benzothiadiazine-1,1-dioxide in 40 cc. of warm acetone is treated with 0.9 g. 4-methyl-dihydropyran and two drops concentrated hydrochloric acid. The solution is allowed to remain at room temperature overnight and then concentrated to dryness in vacuo. A small amount of ether is added to the residue and white crystals of the product, 6-chloro-3,4-dihydro - 7 - sulfamyl - 2 - (4 - methyl-tetrahydro-2-pyranyl)-1,2,4-benzothiadiazine-1,1-dioxide, are obtained.

[By substituting an equivalent amount of 6-trifluoromethyl-3,4-dihydro - 7 - sulfamyl-1,2,4-benzothiadiazine-1,1-dioxide for the 6-chloro-3,4-dihydro-7-sulfamyl-1,2,4-benzothiadiazine-1,1-dioxide and following the procedure given above, the corresponding 6-trifluoromethyl compound may be obtained.]

Example 3

2.55 g. of 6-chloro-3,4-dihydro-7-sulfamyl-1,2,4-benzothiadiazine-1,1-dioxide in 35 cc. of warm acetone is treated with 1 g. 6-ethoxy-dihydropyran and two drops concentrated hydrochloric acid. After remaining overnight at room temperature, the solution is concentrated to dryness in vacuo. The product, 6-chloro-3,4-dihydro-2-(6-ethoxy-tetrahydro - 2 - pyranyl) - 7 - sulfamyl-1,2,4-benzothiadiazine-1,1-dioxide, is collected and recrystallized from acetone.

[By substituting an equivalent amount of 6-trifluoromethyl-3,4-dihydro - 7 - sulfamyl-1,2,4-benzothiadiazine-1,1-dioxide for the 6-chloro-3,4-dihydro-7-sulfamyl-1,2,4-benzothiadiazine-1,1-dioxide and following the procedure given above, the corresponding 6-trifluoromethyl compound may be obtained.]

Example 4

3.2 g. of 6-chloro-3-cyclopentylmethyl-3,4-dihydro-7-sulfamyl-1,2,4-benzothiadiazine-1,1-dioxide in 40 cc. of warm acetone is treated with 0.84 g. dihydropyran and two drops concentrated hydrochloric acid. The solution is allowed to remain at room temperature overnight. The product is then collected and recrystallized from ethanol-water to produce the pure 6-chloro-3-cyclopentylmethyl-3,4-dihydro-7-sulfamyl-2 - (tetrahydro-2-pyranyl)-1,2,4-benzothiadiazine-1,1-dioxide.

[By substituting 6-trifluoromethyl-3-cyclopentylmethyl-3,4-dihydro - 7 - sulfamyl - 1,2,4 - benzothiadiazine-1,1-dioxide for the 6-chloro-3-cyclopentylmethyl-3,4-dihydro-7-sulfamyl - 1,2,4 - benzothiadiazine-1,1-dioxide reactant used in this example, the corresponding trifluoromethyl product may be obtained.]

Example 5

3.8 g. of 3-benzylmethyl-6-chloro-3,4-dihydro-7-sulfamyl-1,2,4-benzothiadiazine-1,1-dioxide is dissolved in 50 cc. of warm acetone. This is treated with 1 g. 4,6-dimethyl-dihydropyran and two drops concentrated hydrochloric acid. After remaining overnight at room temperature, the solution is concentrated to dryness in vacuo. The residue is recrystallized from ethanol to produce the pure 3-benzylmethyl-6-chloro - 3,4 - dihydro-7-sulfamyl-2 - (4,6-dimethyl - 2 - pyranyl) - 1,2,4 - benzothiadiazine-1,1-dioxide.

[By substituting 3-benzylmethyl-6-trifluoromethyl-3,4-dihydro-7-sulfamyl-1,2,4-benzothiadiazine-1,1-dioxide for the 3-benzylmethyl-6-chloro-3,4-dihydro-7-sulfamyl-1,2,4-benzothiadiazine-1,1-dioxide used in this example, the corresponding trifluoromethyl compound may be obtained.]

Example 6

3.2 g. of 6-chloro-3-dichloromethyl-3,4-dihydro-7-sulfamyl-1,2,4-benzothiadiazine-1,1-dioxide in 40 cc. of warm acetone is treated with 0.84 g. dihydropyran and two drops concentrated hydrochloric acid. The solution is allowed to remain overnight at room temperature and then concentrated to dryness in vacuo. The residue thus obtained is recrystallized from ethanol-water to produce the pure 6-chloro-3-dichloromethyl - 7 - sulfamyl-2-(tetrahydro-2-pyranyl)-1,2,4-benzothiadiazine-1,1-dioxide.

[By substituting 6-trifluoromethyl-3-monochloromethyl-3,4-dihydro - 7 - sulfamyl - 1,2,4 - benzothiadiazine-1,1-dioxide for the 6-chloro-3-dichloromethyl-3,4-dihydro-7-sulfamyl-1,2,4-benzothiadiazine-1,1-dioxide used in this example, the corresponding 3-monochloromethyl compound may be obtained. Substitution of the 6-chloro-3-monochloromethyl (or 3-dichloromethyl) reactants for the one used in this example, will yield the corresponding trifluoromethyl derivatives.]

20

Example 7

2.75 g. of 3-cyclopentylmethyl-3,4-dihydro-7-sulfamyl-6-trifluoromethyl-1,2,4-benzothiadiazine-1,1-dioxide is dissolved in 50 cc. of warm acetone and then treated with 0.84 g. dihydropyran and two drops concentrated hydrochloric acid. After remaining overnight the solution is evaporated to one-half its volume, the crystals collected and recrystallized from ethanol-water to produce the pure 3-cyclopentylmethyl - 3,4 - dihydro-7-sulfamyl-6-trifluoromethyl-2-(tetrahydro - 2 - pyranyl)-1,2,4-benzothiadiazine-1,1-dioxide.

What is claimed is:

1. A member of the group consisting of 3,4-dihydro-2H-1,2,4-benzothiadiazine-1,1-dioxides of the formula

in which R₁ represents a member of the group consisting of hydrogen, lower alkyl, lower alkyl substituted by halogen, halo-lower alkyl, lower alkoxy-lower alkyl, lower alkyl-mercaptop-lower alkyl, phenyl-lower alkyl-mercaptop-lower alkyl, lower alkenyl, cycloalkyl having from five to six ring carbon atoms and phenyl-lower alkyl, R_{2'} stands for 2-cycloalkyl having four to six carbon atoms and at least one and at most two atoms of the group consisting of oxygen and sulfur as ring members, and R₃ represents a member of the group consisting of halogen and halogen-lower alkyl, and alkali metal salts thereof.

2. 6 - chloro - 2-R-7 - sulfamyl-3,4-dihydro-2H-1,2,4-benzothiadiazine-1,1-dioxide, wherein R is 2-tetrahydro-2-pyranyl.

3. 6 - chloro - 2-R-7 - sulfamyl-3,4-dihydro-2H-1,2,4-benzothiadiazine-1,1-dioxide, wherein R is 4-methyl-tetrahydro-2-pyranyl.

4. 6 - trifluoromethyl - 2-R-7 - sulfamyl-3,4-dihydro-2H-1,2,4-benzothiadiazine-1,1-dioxide, in which R is 2-cyclo-oxaalkyl having from four to six carbon atoms.

5. 6-chloro-3-halogeno-lower alkyl-2-R-7-sulfamyl-3,4-dihydro-2H-1,2,4-benzothiadiazine-1,1-dioxide, in which lower alkyl has from one to four carbon atoms and R is 2-cyclo-oxaalkyl having from four to six carbon atoms.

6. 6 - trifluoromethyl-3-halogeno-lower alkyl - 2-R-7-sulfamyl - 3,4 - dihydro-2H-1,2,4-benzothiadiazine-1,1-dioxide, in which lower alkyl has from one to four carbon atoms and R is 2-cyclo-oxaalkyl having from four to six carbon atoms.

7. 6-chloro-2-R-3-phenyl-lower alkyl-7-sulfamyl-3,4-dihydro-2H-1,2,4-benzothiadiazine-1,1-dioxide, in which lower alkyl has from one to four carbon atoms and R is 2-cyclo-oxaalkyl having from four to six carbon atoms.

17

8. 6 - trifluoromethyl-2-R-3-phenyl-lower alkyl - 7 - sulfamyl-3,4-dihydro-2H-1,2,4-benzothiadiazine - 1,1 - dioxide, in which lower alkyl has from one to four carbon atoms and R is 2-tetra-hydropyranyl.

9. 6 - chloro-2,3-bis-(tetrahydro-2-pyranyl)-7-sulfamyl-3,4-dihydro-2H-1,2,4-benzothiadiazine-1,1-dioxide. 5

10. 6 - trifluoromethyl-2,3-bis-(tetrahydro-2-pyranyl)-7-sulfamyl - 3,4 - dihydro-2H-1,2,4-benzothiadiazine-1,1-dioxide.
